UNITED STATES PATENT OFFICE.

AMADEE SPADONE, OF NEW YORK, N. Y.

DESIGN FOR A BELT.

SPECIFICATION forming part of Design No. 24,679, dated September 17, 1895.

Application filed May 14, 1895. Serial No. 549,321. Term of patent 7 years.

To all whom it may concern:

Be it known that I, AMADEE SPADONE, a citizen of the United States, residing in the city, county, and State of New York, have invented and produced a new and original Design for a Belt, of which the following is a specification.

The leading feature of my design is a belt of essentially the configuration and representation shown in the accompanying drawings, in which—

Figure 1 exhibits a sectional view of a belt embodying my design, showing the outline thereof, which is an essential characteristic of my design. Fig. 2 is an isometric view of a belt embodying my design, and Fig. 3 is an

isometric view of a belt embodying my design.

In the drawings, A is the body portion of the belt, which body portion is substantially ^{2c} plane with substantially parallel edges e e, from which project curved and pointed flanges B B, having the swell b and the channel C therein.

What I claim is—

The design for a belt, substantially as herein shown and described. ²⁵

AMADEE SPADONE.
